MECHANICAL SHOVELING DEVICE

Charles E. Stoltz, Chicago, Ill., assignor, by mesne assignments, to Goodman Manufacturing Company, Chicago, Ill., a corporation of Illinois

Application December 9, 1935, Serial No. 53,453
Renewed July 17, 1937

25 Claims. (Cl. 214—132)

This invention relates to improvements in mechanical shoveling devices of the mucking type adapted to shovel in confined spaces, such as mines, and has as its principal objects to provide a novel means driven in timed relation with movement of the scoop, for aligning the scoop with its supporting truck, so that it may discharge material rearwardly beyond the rearward end of the truck. Another object of my invention is to so arrange the aligning mechanism that the centering operation will be delayed until the scoop has been elevated above the ground a certain predetermined distance.

This application is a continuation in part of a prior application, Serial No. 17,597, filed April 22, 1935, now Patent No. 2,070,415, dated February 9, 1937, and differs therefrom chiefly in the arrangement of the centering mechanism, in that the centering mechanism herein described and illustrated is arranged so as to come into operation after the scoop has been elevated above the ground a certain distance to enable said scoop to gather a full load and prevent said scoop from engaging and scattering material on the ground during the centering operation.

My invention may be more clearly understood with reference to the accompanying drawings wherein:

Figure 1 is an enlarged side elevation of a shoveling machine with parts broken away and shown in substantially longitudinal section, illustrating one form in which my invention may be embodied;

Figure 2 is a top plan view of the shoveling machine shown in Figure 1, with certain parts broken away and shown in horizontal section;

Figure 3 is an enlarged fragmentary transverse sectional view taken through the centering mechanism in order to more clearly illustrate certain details thereof;

Figure 4 is an enlarged fragmentary plan view of the centering mechanism with certain parts broken away and shown in horizontal section in order to more clearly illustrate certain details of said centering mechanism not shown in Figure 3; and

Figure 5 is a detail plan view of the centering mechanism showing the parts in a different position than in Figure 4.

In the drawings, the main elements of the machine shown are somewhat similar to those described in my aforementioned prior application, so will only be described herein insofar as is necessary to clearly illustrate one form in which my present invention may be embodied.

In the form shown, the shoveling machine consists of a track mounted truck 10 having a turntable or shovel supporting frame 11 mounted thereon. Said turntable forms a supporting means for a scoop 12 pivotally mounted on the free ends of supporting beams 13 and 13a. Said supporting beams are freely mounted at their opposite ends on a shaft 14 extending transversely of said turntable and journaled at its ends in suitable bearing members, indicated by reference characters 15, 15.

The machine is moved along the track during the shoveling operation for feeding the machine into material it is desired to load, and is propelled along the rails by means of a motor 16 mounted on the under side of the truck 10. Said motor may be of any type well known to those skilled in the art, but is herein preferably shown as being an air motor of an ordinary construction and has driving connection with track wheels 17, 17 in a suitable manner which will not herein be shown or described in detail, since it is no portion of my present invention.

The turntable or shovel frame 11 includes a relatively flat plate 18 having a cut out central portion adapted to have the lower portion of a housing 19 extend therethrough and be mounted therein in a suitable manner. Said housing is journaled on a shouldered bearing member 23 mounted on a member 24 secured to and extending upwardly from the central portion of the top side of said truck. Said last-mentioned member is provided with a pair of depending integrally formed keys 25, 25 adapted to engage suitable slots 26, 26 formed in the top side of said truck frame and hold said member from pivotal movement with respect to said truck. Said plate has an annular race 20 mounted on the bottom side thereof which race has a plurality of balls 21, 21 carried therein adapted to engage and support said plate on an annular wearing strip 22 mounted on the upper surface of the truck 10.

The means for elevating said scoop to a discharge position includes a pair of sprockets 27, 27 mounted on the outer ends of a transverse shaft 45 28 journaled in the beams 13 and 13a. Said sprockets mesh with arcuate racks 29, 29 mounted on the inner sides of vertically disposed side plates 30, 30 extending upwardly from opposite sides of said turntable. The drive to said sprockets includes a sprocket 33 keyed on said shaft outwardly of the beam 13 and inwardly of the respective sprocket 27. A drive chain 34 meshes with said sprocket and a sprocket 35 on the transversely extending shaft 14. A motor 36, 36

herein preferably shown as being of a usual air type, is mounted at the rearward end of the turntable 11 and drives said last-named sprocket and the shaft 14 by a chain and sprocket drive, generally indicated by reference character 37.

The scoop 12 is mounted on the free ends of the beams 13 and 13a by means of a bracket 48 extending rearwardly from the upper end of said scoop and a shaft 41 extending through said bracket and beams and held from lateral movement with respect thereto in a suitable manner. Thus, said scoop depends from said beams and turntable and is supported for pivotal movement with respect thereto, so that its forward end 15 may be disposed adjacent the ground when said beams are in an extreme forward position to permit said scoop to gather material from the ground below the level of the track (see Figure 1).

20 A pair of parallel-spaced cylinders 43, 43 is provided to pivot said scoop and move it along the ground. Said cylinders are mounted for slideable movement with respect to the beams 13 and 13a by means of a shaft 44 mounted at its ends 25 in said beams and pivotally mounted on the inner ends of pistons 45, 45 and extending through suitable slots 46, 46 formed in said cylinders. The forward ends of said cylinders are provided with caps 47, 47 threaded thereon, 30 which are pivotally connected to said scoop by means of a transverse shaft 48 pivotally connected to a bracket 49 disposed beneath the bracket 40.

Fluid under pressure may be admitted to the 35 cylinders 43, 43 through the caps 47, 47 to extend said cylinders and pivot said scoop about the axis of the shaft 41 by means of a suitable system of piping and control mechanism, which is not herein shown or described since it forms 40 no portion of my present invention.

During upward and rearward movement of said scoop, pressure is usually held in the cylinders 43, 43 until said scoop reaches a discharge position so that said scoop may be held in such a 45 position to permit material to be readily discharged therefrom by gravity, as is shown by dotted lines in Figure 1.

When returning to an initial shoveling position, said scoop is slidably supported on guide 50 cams 50, 50 mounted on the inside of the side plates 30, 30. Said guide cams are engaged by rollers 51, 51 on the outer ends of the shaft 48 and the upper ends of said guide cams are formed to engage said rollers and form a means for 55 stopping rearward movement of said scoop. Said supporting cams operate on principles similar to those described in my prior application, so will not herein be shown or described in detail, since they form no part of my present invention.

60 Referring now in particular to the novel centering mechanism for aligning the scoop and turntable with the truck frame when the scoop is in a discharge position, as illustrated by dotted lines in Figure 1, so that material may be 65 discharged rearwardly therefrom into a suitable receptacle, such as a mine car 52, the portion of the shaft 14 inwardly of the beams 13 and 13a is herein shown as being oppositely threaded towards the center thereof (see Figures 3 and 4). 70 As herein shown, said shaft is provided with a left hand threaded portion 53 extending inwardly from the left hand beam 13, and a right hand threaded portion 54 extending inwardly from the right hand beam 13a. Said threaded portions extend to a position disposed substantially

midway between the beams 13 and 13a, and are herein shown as terminating at a point offset from the center of said turntable. The threaded portion 53 has a nut 55 threaded thereon, and the threaded portion 54 has a nut 56 threaded 5 thereon. Said nuts are positioned so as to be adjacent the beams 13 and 13a when the scoop is in a lowered position, so that they will simultaneously move toward the center of the turntable upon rotation of said shaft in one direction and upon upward movement of said scoop.

A pair of pivoted arms 57, 57, herein shown as being pivoted for movement about an axis coaxial with the turning axis of the turntable, is adapted to be operatively connected with the 15 nuts 55 and 56, respectively. Said arms are provided with interleaving inner portions which are pivotally mounted on a vertical stub shaft 58 mounted on and extending upwardly from the member 24. The outer ends of said pivoted arms 20 are adapted to engage a fixed abutment 59, herein shown as being a squared member extending upwardly from the outer end of a forwardly extending arm 60 formed integral with the member 24. Thus, when the turntable is 25 turned by hand until the free end of one of the arms 57 engages the abutment 59, pivotal movement of said arm will pivot said turntable, and when both of said arms engage the fixed 30 abutment 59, said turntable will be locked in an aligned position with respect to said truck, as is illustrated in detail in Figure 5.

The connection between the nuts 55 and 56, and the arms 57, 57 for pivotally moving said arms upon movement of said nuts, herein comprises a slotted arm 61 formed integral with the nut 55 and extending downwardly and forwardly therefrom, and a slotted arm 63 formed integral with the nut 56 and extending downwardly and forwardly therefrom. It should herein be noted that the slotted portion of the arm 61 is disposed inwardly of the nut 56 and that the slotted portion of the arm 61 is disposed on the outer portion of the nut 55 to compensate for the fact that the threaded portions of the shaft 14 terminate eccentric of the center of the turntable 45.

The slotted portion of the arm 61 is of an L-shaped formation having a base extending inwardly along and substantially parallel with the forward side of said nut and a stem extending longitudinally forwardly from the outer end of said base. In a like manner, the slotted portion of the slotted arm 63 is of a similar formation so that the ends of the bases of each of said slots 55 may extend inwardly toward each other, and said last-named slotted portion is herein shown as being spaced above the slotted portion of the arm 61 so that the ends of the bases of the respective slots may overlap each other when the scoop is in a discharge position (see Figure 5). Said slotted portions of said slotted arms are adapted to engage pins 64, 64 secured to and extending upwardly from the members 57, 57 intermediate the ends thereof.

It will be seen from the foregoing that when the members 57, 57 and nuts 55 and 56 are positioned adjacent the inner sides of the beams 13 and 13a, respectively, as is shown in Figure 4, and the sprocket 35 is being rotatably driven by the motor 36 in a direction to elevate said scoop, that said nuts will simultaneously move inwardly toward each other a distance determined by the length of the base of said slots before they will 75

cause pivotal movement of the members 51, 57 towards each other.

Thus, when the turntable is turned so that the scoop 12 is positioned to one side or the other of the center line of the truck 10, said scoop may gather its load from the ground and be elevated upwardly a certain predetermined distance before the centering mechanism comes into operation. This enables the gathering operation of the scoop 10 to be more readily controlled than formerly, and prevents the scoop from hitting and scattering loose material on the ground during the centering operation.

While I have herein shown and described 15 one form in which my invention may be embodied, it will be understood that the construction and arrangement of the various parts may be changed or altered without departing from the spirit or scope thereof. Furthermore, I do not 20 wish to be construed as limiting myself to the precise construction illustrated, excepting as it may be limited in the appended claims.

I claim as my invention:

1. In a power shovel, a truck, a turntable thereon, a beam pivoted on said turntable for movement about a horizontal axis, a scoop on the free end of said beam adapted to be elevated by said beam from a loading position in front of said truck to a discharge position over the rear end of 30 said truck, means for swinging said beam in a vertical plane including a motor, and means driven by said motor in timed relation with swinging movement of said beam for aligning said scoop with said truck when said scoop reaches a discharge position.

2. In a power shovel, a truck, a turntable thereon, a beam pivoted on said turntable for movement about a horizontal axis, a scoop on the free end of said beam adapted to be elevated by said beam from a loading position in front of said truck to a discharge position over the rear end of said truck, means for swinging said beam including a motor and means driven by said motor in timed relation with swinging movement of said beam for aligning said scoop with said truck when said scoop reaches a discharge position and locking said turntable in such a position until said scoop is moved in a direction towards an initial gathering position.

3. In a power shovel, a truck, a turntable thereon, a beam pivoted on said turntable for movement about a horizontal axis, a scoop on the free end of said beam adapted to be elevated by said beam from a loading position in front of said truck to a discharge position over the rear end of said truck, power-operated means for swinging said beam in a vertical plane including a motor, and means driven by said motor for aligning said scoop with said truck when said scoop reaches a discharge position comprising a stationary member on said truck and a member adapted to engage said stationary member, said member being mounted on said turntable for movement transversely thereof towards the center of said turntable, as said beam is moving toward the rear of said truck.

4. In a power shovel, a truck, a turntable thereon, a beam pivoted on said turntable for movement about a horizontal axis, a scoop on the free end of said beam adapted to be elevated by said beam from a loading position in front of said truck to a discharge position over the rear end of said truck, power-operated means for swinging said beam and moving said scoop 75 to a discharge position including a motor, and

means driven by said motor for aligning said scoop with said truck when said scoop reaches a discharge position comprising a stationary member on said truck and a pair of members mounted on said turntable, one of said members being adapted to engage said stationary member when said turntable is turned to one side or the other of the center line of said truck and said members being transversely movable with respect to said turntable from the outer portion 10 to the center thereof as said beam is moving towards the rear of said truck.

5. In a power shovel, a truck, a turntable thereon, a beam pivoted on said turntable for movement about a horizontal axis, a scoop on the free end of said beam adapted to be elevated by said beam from a loading position in front of said truck to a discharge position over the rear end of said truck, power-operated means for swinging said beam and moving said 15 scoop to a discharge position including a motor, and means driven by said motor for aligning said scoop with said truck when said scoop reaches a discharge position comprising a stationary member on said truck, a shaft driven by said 20 motor, a pair of nuts mounted on said shaft, one of said nuts being adapted to engage said member depending upon which side of the truck said turntable is turned and said nuts being simultaneously movable towards the center of said 25 turntable as said beam is moving towards the rear of said truck.

6. In a power shovel, a truck, a turntable thereon, a beam pivoted on said turntable for movement about a horizontal axis, a scoop on the free end of said beam adapted to be elevated by said beam from a loading position in front of said truck to a discharge position over the rear end of said truck, power-operated means for swinging said beam and moving said scoop to a 30 discharge position including a motor, and means driven by said motor for aligning said scoop with said truck when said scoop reaches a discharge position comprising a stationary member on said truck, a shaft having screw threads thereon 35 threaded in opposite directions from the center thereof and a pair of nuts threaded on said shaft, said nuts being adapted to be positioned adjacent the outer end of said shaft when said scoop is positioned adjacent the ground and being movable towards the center of said shaft as said beam moves upwardly.

7. In a power shovel, a truck, a turntable thereon, a beam pivoted on said turntable for movement about a horizontal axis, a scoop on the free end of said beam adapted to be elevated by said beam from a loading position in front of said truck to a discharge position over the rear end of said truck, power-operated means for swinging said beam and moving said 45 scoop to a discharge position including a motor, and means driven by said motor for aligning said scoop with said truck when said scoop reaches a discharge position comprising a stationary member on said truck, a transversely extending shaft on said turntable, a drive connection from said motor to said shaft, a pair of nuts mounted on said shaft and movable therealong upon rotation thereof, said nuts being simultaneously movable towards the center of 50 said turntable as said beam is moving towards the rear of said truck.

8. In a power shovel, a truck, a turntable thereon, a beam pivoted on said turntable for movement about a horizontal axis, a scoop on the 55

- the free end of said beam adapted to be elevated by said beam from a loading position in front of said truck to a discharge position over the rear end of said truck, power-operated means 5 for swinging said beam and moving said scoop to a discharge position including a motor, and means driven by said motor for aligning said scoop with said truck when said scoop reaches a discharge position comprising a stationary member on said truck, a transversely 10 extending shaft on said turntable coaxial with the pivotal axis of said beam, said shaft having screw threads threaded in opposite directions from the center thereof, and a pair of nuts 15 threaded on said shaft for movement in opposite directions along said shaft upon rotation thereof, said nuts being movable towards the center of said shaft as said beam is moving towards the rear of said truck.
- 20 9. In a power shovel, a truck, a turntable thereon, a beam pivoted on said turntable for movement about a horizontal axis, a scoop on the free end of said beam adapted to be elevated by said beam from a loading position in front 25 of said truck to a discharge position over the rear end of said truck, means for swinging said beam including a motor and drive mechanism driven thereby, and means driven by said drive mechanism in timed relation with swinging movement 30 of said beam and arranged coaxial with the pivotal axis of said beam for aligning said scoop with said truck when said scoop reaches a position for the discharge of material from the rear end of said truck.
- 35 10. In a power shovel, a truck, a turntable thereon, a beam pivoted on said turntable for movement about a horizontal axis, a scoop on the free end of said beam adapted to be elevated by 40 said beam from a loading position in front of said truck to a discharge position over the rear end of said truck, means for swinging said beam including a motor, and means driven by said 45 drive mechanism in timed relation with swinging movement of said beam and arranged coaxial with the pivotal axis of said beam for aligning said scoop with said truck when said scoop reaches a position for the discharge of material from the rearward end of said truck comprising 50 a rotatable member having a pair of nuts movable therealong in opposite directions towards the center thereof as said beam moves in an upward direction.
- 55 11. In a power shovel, a truck, a turntable thereon, a beam pivoted on said turntable for movement about a horizontal axis, a scoop on the free end of said beam adapted to be elevated by 60 said beam from a loading position in front of said truck to a discharge position over the rear end of said truck, power-operated means for swinging said beam including a motor, and means driven by said motor for aligning said scoop with said truck when said scoop reaches a discharge position comprising a rotatable shaft mounted 65 on said turntable and extending transversely thereof, a pair of nuts on said shaft and movable therealong in opposite directions towards the center of said turntable as said scoop is moving in an upward direction, a stationary member on 70 said truck, and means associated with said nuts adapted to engage said stationary member.
- 75 12. In a power shovel, a truck, a turntable thereon, a beam pivoted on said turntable for movement about a horizontal axis, a scoop on the free end of said beam adapted to be elevated 75 by said beam from a loading position in front of said truck to a discharge position over the rear end of said truck, power-operated means for swinging said beam including a motor, and means driven by said motor for aligning said scoop with said truck when said scoop reaches a discharge position comprising a rotatable shaft having screw threads thereon threaded in opposite directions from the center thereof, said shaft being mounted on said turntable and extending transversely thereof and having a pair of nuts threaded thereon and movable in opposite directions towards the center of said turntable as said scoop is moving in an upward direction, a stationary member on said truck, and means associated with said nuts for engagement with said stationary member. 15
13. In a power shovel, a truck, a turntable thereon, a beam pivoted on said turntable for movement about a horizontal axis, a scoop on the free end of said beam adapted to be elevated by 20 said beam from a loading position in front of said truck to a discharge position over the rear end of said truck, means for swinging said beam in a vertical plane including a motor, and means 25 driven by said motor in timed relation with swinging movement of said beam and initially operable when said scoop has been moved upwardly to a predetermined position for aligning said scoop with said truck when said scoop reaches its discharge position. 30
14. In a power shovel, a truck, a turntable thereon, a beam pivoted on said turntable for movement about a horizontal axis, a scoop on the free end of said beam adapted to be elevated by 35 said beam from a loading position in front of said truck to a discharge position over the rear end of said truck, means for swinging said beam including a motor, and means driven by said 40 motor in timed relation with swinging movement of said beam and initially operable when said scoop has been moved upwardly to a predetermined position for aligning said scoop with said truck when said scoop reaches its discharge position comprising a member on said turntable 45 translationally movable transversely thereof, and another member engageable with an abutment fixed from movement with respect to said turntable and moved by said first-mentioned member translationally of said turntable after said first-mentioned member has moved a predetermined 50 distance across said turntable. 55
15. In a power shovel, a truck, a turntable thereon, a beam pivoted on said turntable for movement about a horizontal axis, a scoop on the free end of said beam adapted to be elevated by 60 said beam from a loading position in front of said truck to a discharge position over the rear end of said truck, means for swinging said beam including a motor, and means driven by said 65 motor in timed relation with swinging movement of said beam and initially operable when said scoop has been moved upwardly to a predetermined position for aligning said scoop with said truck when said scoop reaches a discharge position, said last-named means comprising a slotted member movable transversely of said turntable, a pivoted member engaged by said slotted member and adapted to engage an abutment fixed from movement with respect to said turntable whereby 70 said slotted member may move a predetermined distance without moving said pivoted member and movement of said slotted member an additional distance will cause pivotal movement of said pivoted member. 75

16. In a power shovel, a truck, a turntable thereon, a beam pivoted on said turntable for movement about a horizontal axis, a scoop on the free end of said beam adapted to be elevated by said beam from a loading position in front of said truck to a discharge position over the rear end of said truck, means for swinging said beam including a motor, and means driven by said motor in timed relation with swinging movement of said beam and initially operable when said scoop has been moved upwardly to a predetermined position for aligning said scoop with said truck when said scoop reaches its discharge position, said last-named means comprising a threaded shaft rotatably driven by said motor, a nut threaded thereon having a slotted arm extending therefrom, a pivoted arm adapted to be slidably engaged with said slotted arm intermediate its ends and adapted to engage an abutment fixed from movement with respect to said turntable at its free end, so that said slotted arm may move a predetermined distance and movement of said slotted arm a further distance will cause pivotal movement of said pivoted arm.
- 25 17. In a power shovel, a truck, a turntable thereon, a beam pivoted on said turntable for movement about a horizontal axis, a scoop on the free end of said beam adapted to be elevated by said beam from a loading position in front of said truck to a discharge position over the rear end of said truck, means for swinging said beam including a motor, and means driven by said motor in timed relation with swinging movement of said beam for aligning said scoop with said truck when said scoop reaches its discharge position comprising a fixed abutment on said truck, a shaft on said turntable rotatably driven by said motor, a pair of nuts mounted on said shaft and movable in opposite directions therealong upon rotation thereof, a pair of members pivoted for movement about coaxial axes and having free ends adapted to engage said fixed abutment, and arms extending from said nuts, each of said arms being adapted to engage an associated pivoted member intermediate the ends thereof for pivotally moving said members towards the center of said turntable upon movement of said scoop in an upward direction.
- 40 18. In a power shovel, a truck, a turntable thereon, a beam pivoted on said turntable for movement about a horizontal axis, a scoop on the free end of said beam adapted to be elevated by said beam from a loading position in front of said truck to a discharge position over the rear end of said truck, means for swinging said beam including a motor, and means driven by said motor in timed relation with swinging movement of said beam and initially operable when said scoop has been moved upwardly to a predetermined position for aligning said scoop with said truck when said scoop reaches its discharge position comprising a fixed abutment on said truck, a shaft on said turntable and rotatably driven by said motor, a pair of nuts mounted on said shaft and movable in opposite directions therealong upon rotation thereof, a pair of members pivoted for movement about coaxial axes and having free ends adapted to engage said fixed abutment, an arm extending from each of said nuts, each of said arms having a slot therein adapted to form a means for pivoting said members upon rotation of said shaft, said slots being so formed that said arms may move a predetermined distance towards the center of said turntable before causing pivotal movement of said arms.
- 45 19. In a power shovel, a truck, a turntable thereon, a beam pivoted on said turntable for movement about a horizontal axis, a scoop on the free end of said beam adapted to be elevated by said beam from a loading position in front of said truck to a discharge position over the rear end of said truck, means for swinging said beam including a motor, and means driven by said motor in timed relation with swinging movement of said beam and operable when said scoop has been moved upwardly to a predetermined position for aligning said scoop with said truck when said scoop is in a discharge position comprising a fixed abutment on said truck, a shaft on said turntable and rotatably driven by said motor, a pair of nuts mounted on said shaft and movable in opposite directions therealong upon rotation thereof, a pair of members pivoted for movement about coaxial axes and having free ends adapted to engage said fixed abutment, an arm extending from each of said nuts, each of said arms having a slot therein adapted to form a means for pivoting said members upon rotation of said shaft, said slots having engaging walls of an L-shaped formation whereby said nuts and arms may move a predetermined distance towards the center of said turntable before causing pivotal movement of said arms.
- 50 20. In a shoveling machine, a truck, a turntable thereon, a scoop mounted on said turntable for movement from a loading position in front of said truck to a discharge position over the rear end of said truck, means for moving said scoop from the front to rear of said truck including a motor, and a shaft driven by said motor in timed relation with movement of said scoop having means extensible therealong for aligning said scoop with said truck when said scoop reaches a discharge position.
- 55 21. In a shoveling machine, a truck, a turntable thereon, a scoop mounted on said turntable for movement from a loading position in front of said truck to a discharge position over the rear end of said truck, means for moving said scoop from the front to rear of said truck including a motor, and means driven by said motor in timed relation with movement of said scoop and initially operable when said scoop has moved upwardly to a predetermined position for aligning said scoop with said truck when said scoop reaches its discharge position.
- 60 22. In a shoveling machine, a truck, a turntable thereon, a scoop mounted on said turntable for movement from a loading position in front of said truck to a discharge position over the rear end of said truck, means for moving said scoop from the front to rear of said truck including a motor, and means driven by said motor in timed relation with movement of said scoop for aligning said scoop with said truck when said scoop reaches a discharge position, and locking said scoop and turntable in such a position until said scoop is again moved in a direction towards an initial gathering position.
- 65 23. In a shoveling machine, a truck, a turntable thereon, a scoop mounted on said turntable for movement from a loading position in front of said truck to a discharge position over the rear end of said truck, means for moving said scoop from the front to rear of said truck including a motor, and means driven by said motor in timed relation with movement of said scoop for aligning said scoop with said truck when said scoop reaches its discharge position.

- scoop reaches a discharge position comprising a stationary member, a shaft driven by said motor, a pair of nuts on said shaft and movable towards the center thereof upon rotation of said shaft 5 in one direction, one of said nuts being adapted to engage said stationary member for turning said turntable upon movement thereof towards the center of said truck.
24. In a shoveling machine, a truck, a turntable thereon, a scoop mounted on said turntable for movement from a loading position in front of said truck to a discharge position over the rear end of said truck, means for moving said scoop from the front to rear of said truck including a motor, and means driven by said motor in timed relation with movement of said scoop and initially operable when said scoop has moved upwardly to a predetermined position for aligning said scoop with said truck when said scoop reaches its discharge position comprising a member 10 on said turntable translationally movable transversely thereof, and another member engageable with an abutment fixed from movement with respect to said turntable and moved by said 15 first-mentioned member translationally of said

turntable after said first-mentioned member has moved a predetermined distance across said turntable.

25. In a shoveling machine, a truck, a turntable thereon, a scoop mounted on said turntable 5 for movement from a loading position in front of said truck to a discharge position over the rear end of said truck, means for moving said scoop from the front to rear of said truck including a motor, and means driven by said motor in timed 10 relation with movement of said scoop and initially operable when said scoop has moved upwardly to a predetermined position for aligning said scoop with said truck when said scoop reaches its discharge position, said last-named means comprising a slotted member movable transversely of said turntable, a pivoted member engaged by said slotted member and adapted to engage an abutment fixed from movement with respect to said turntable whereby said slotted member may 15 move a predetermined distance without moving said pivoted member and movement of said slotted member an additional distance will cause pivotal movement of said pivoted member.

CHARLES E. STOLTZ. 25
